UNITED STATES PATENT OFFICE.

EDGAR E. BARNETT, OF KREMLIN, OKLAHOMA TERRITORY.

BELT-TOOL.

No. 851,482.

Specification of Letters Patent.

Patented April 23, 1907.

Application filed December 14, 1906. Serial No. 347,851.

To all whom it may concern:

Be it known that I, EDGAR E. BARNETT, a citizen of the United States, and a resident of Kremlin, in the county of Garfield, Oklahoma Territory, have invented a new and Improved Belt-Tool, of which the following is a full, clear, and exact description.

This invention is an improved belt tool having means for punching and cutting holes in the ends of a belt such as are generally provided to receive the lacing; also embodying in its construction a device for drawing the lacing through these holes in the belt, and lacing the ends thereof together.

15 The object of the invention is to combine the above means into a unitary, simple structure in the manner that they can be successfully used without interference with each other, and to further provide for the adjustment of the punch to cut holes of varying size, and the enclosing or encasing of the punch when the same is not in use.

Reference is to be had to the accompanying drawings forming a part of this specification, in which similar characters of reference indicate corresponding parts in all the figures.

Figure 1 is a side view of my improved tool partly in central section, and Fig. 2 is a perspective view of the punch.

30 In carrying out my invention, I employ a hollow or tubular handle 1, having formed preferably as an integral part at its upper end, an offset jaw 2, the connecting portion between the handle 1 and jaw 2 preferably being disk-shaped as is usual in plier construction. 3 indicates a second handle, which is arranged by the side of the handle 1 and is preferably formed as a long, conical body slightly shorter than the handle 1 and 35 providing an awl or other pointed instrument. The handle 3 is constructed with a disk portion 4, which is pivotally connected at its center to the offset portion of the handle 1 by a screw or other device 5. The disk 4 is extended beyond the screw or pivot 5, where it is formed into a jaw 2^a in all respects alike and opposed to the jaw 2.

The handle 1 is provided with a longitudinal slot 6, from which project at one side a series of L-shaped notches 7. This slot and the adjacent notches are for the purpose of

receiving the body of a screw or pin 8 threaded into the shank of a punch 9. The punch 9, as best shown in Fig. 2, is in the nature of a pointed body preferably of semi-conical form, which will, as is obvious, cut a round hole in a piece of leather when forced through it and given one or more turns. The shank of the punch 9, which is cylindrical to slidably fit the bore of the hollow handle, is connected 55 to a screw-threaded plug 10 threaded into the opposite end of the handle, through the intermediary of a spiral spring 11, said spring tending at all times to draw the punch within the handle, which acts as a protective casing 60 for the punch when the latter is not in use.

In the use of the punch, it is withdrawn to project beyond the end of the handle a distance according to the size of the hole to be 70 cut, and locked in this position by turning it to engage the screw 8 with one of the notches 7. The punch can now be forced through the material to be cut until the end of the handle 1 is reached, which will perform the 75 function of a stop and enable the user to make any number of holes required of uniform size. When the screw 8 and its engaged notch 7 are disengaged, the spring 11 will withdraw the punch within the handle, 80 as is obvious.

Having thus described my invention I claim as new and desire to secure by Letters Patent:

1. A belt tool comprising a hollow handle 85 having a longitudinal slot therein with notches formed in one edge of the slot, a punch slidably fitting the handle having means for engaging said slot and notches, a plug threaded in the end of the handle opposite the punch, and a spring connecting the plug and punch together.

2. A belt tool comprising a hollow handle, a punch slidably fitting the handle, means for adjustably locking the punch within the 95 handle comprising a plurality of L-shaped notches, and a projection carried by the punch, and a spring normally tending to draw the punch within the handle.

3. A belt tool comprising a hollow handle, 100 a tapered punch having a shank slidably fitting the handle, means for locking the punch

within the handle to project varying distances beyond the end thereof whereby the end of the handle will form a stop adapting the punch to cut uniform openings of various sizes and a spring normally tending to draw the punch within the handle.

In testimony whereof I have signed my

name to this specification in the presence of two subscribing witnesses.

EDGAR E. BARNETT.
